(57) CLAIM

The ornamental design for a combined bottle and applicator for cosmetic products, as shown and described.

DESCRIPTION

1.1 is a front view of the combined bottle and applicator for cosmetic products in closed form;

1.2 is a right side view thereof;

1.3 is a back view thereof;

1.4 is a top view thereof;

1.5 is a front view thereof in exploded form;

1.6 is a right side view thereof in exploded form; and

1.7 is a back view thereof in exploded form.

The broken lines showing of printed indicia and the applicator tip are for the purpose of exemplary adornments and features that form no part of the claimed design.

“CLARINS” is a registered trademark of CLARINS SOCIETE ANONYME FRANCE.
